BARREL-MAKING MACHINE AND METHOD

Application filed March 31, 1927, Serial No. 179,880. Renewed August 8, 1931.

This invention relates to the manufacture of articles from pulped fibrous material or paper forming stock, and particularly to the manufacture of non-plane surfaced boards, slats or the like, such as barrel or keg staves, from such pulped fibrous material.

One of the principal objects of this invention is to provide as a new article of manufacture, a curved board, slat or the like, such as a barrel stave, formed of pulped fibrous material; and to provide containers or barrels formed from this material.

Another object of this invention is to provide a method for making articles of the character mentioned from pulped fibrous material.

Still another object of this invention is to provide apparatus for carrying out the above method.

Other objects and advantages of this invention will be apparent from the following description when taken in connection with the accompanying drawings.

In the drawings in which like characters of reference designate like parts throughout the several views thereof;

Figs. 1, 2 and 3 are diagrammatic elevations of apparatus for carrying out the method of this invention, the several views when placed end to end disclosing the complete machine;

Fig. 4 is a side elevation of a cooperating set of shaping rolls constructed in accordance with this invention;

Fig. 5 is a vertical sectional view on the line 5—5 of Fig. 4;

Fig. 6 is a side elevation of a barrel stave before cooping made from pulped fibrous material;

Fig. 7 is an end elevation of the stave of Fig. 6;

Figs. 8 and 9 are side and end elevations respectively of a barrel stave after cooping;

Fig. 10 is an elevation of an assembled barrel made in accordance with this invention;

Fig. 11 is a side elevation of a modified form of cooperating shaping rolls;

Fig. 12 is a vertical sectional view on the line 12—12 of Fig. 11; and

Figs. 13 and 14 are side and end elevations

respectively of a barrel stave as formed on the shaping rolls of Figs. 11 and 12.

The present invention provides a method of forming non-plane surfaced boards, slats or the like from paper-forming stock or pulped fibrous material. This pulped fibrous material may be derived from any suitable source, and may be wood-pulp, straw-pulp, pulped fibrous grasses, or any of the usual pulped material used for paper-forming or board-forming stock. While the invention is particularly described in connection with the manufacture of barrel or keg staves, and the production of barrels or kegs as the completed products, it is to be understood that the invention is also applicable to the manufacture of other types of non-plane surfaced fibrous articles, such as non-plane building boards, insulating boards, slats and the like.

The method of this invention is particularly applicable to the continuous formation of these articles, or the manufacture of these articles in a traveling or continuously moving stream. This method comprises essentially the forming of the pulped fibrous material into a traveling board web, the shaping of this traveling board web during formation and while still plastic to the desired shape of the articles being manufactured, and drying the formed and shaped web. The shaping of the plastic traveling web is accomplished by a pressing action between shaping surfaces, after the web has been sufficiently processed so that it is capable of sustaining its own weight. The traveling web may be said to be molded to the shape of the articles being manufactured. The formed non-plane surface of the web is preferably preserved by drying on conveying surfaces shaped to correspond to the shape of the web. The dried and shaped web is then cut up in any desired manner into the formed articles, which may be further processed as by tapering, beveling the edges, and the like, to finish the articles.

Referring to the drawings, in which is disclosed a preferred embodiment of apparatus for carrying out the above method, Figs. 1, 2 and 3 illustrate in diagrammatic elevation a complete machine for the manufacture of barrel or keg staves. The complete machine

comprises essentially a forming part or machine A, shaping means B to shape the board web during formation, drying means C for drying the formed and shaped web, and cutters or slitters D. The forming machine A may be of any suitable conventional character. As herein illustrated it comprises a cylinder mold having a tank 11 for containing a supply of board-forming stock, a cylinder roll 12 dipping therein, and a pressure roller 13 running on top of the cylinder roll 12 in the usual manner. Upon rotation of the cylinder roll 12 within the tank 11, a layer of the stock is picked up upon the surface of the roll 12, which rotates in the direction shown, and is squeezed and formed into a web between the pressure roller 13 and roll 12. While only one board-forming cylinder mold is illustrated, it is to be understood that two or more cylinder molds could be provided in series to form a board of the desired thickness, as is well understood in the art.

From the cylinder mold, the board web is transferred and engaged between two endless traveling felts 20 and 21, which felts travel over a plurality of guide pulleys 22 and 23 respectively, each felt being provided with a suitable tensioning pulley 24. The board web supported between the two felts 20 and 21 is passed between a plurality of pressure rolls comprising upper and lower rolls 26 and 27. These rolls may be made adjustable toward each other in the usual manner, and serve as squeeze rolls to squeeze a certain percentage of the remaining water out of the board under formation, these rolls serving to extract sufficient water from the web so that it is in proper condition to be passed through the first wet press indicated at 28.

40 This first press may be of conventional construction, and consists of upper and lower press rolls mounted for adjustment relative to each other, and between which the board web is passed after passing through the sets 45 of pressure rollers 26 and 27.

After leaving the first press, the wet web is shown as being received by and supported between traveling felts 30 and 31, which felts travel over a plurality of supporting and tensioning pulleys, similar to the construction for the felts 20 and 21. The board web thus supported between these felts 30 and 31 is passed through a second wet press indicated at 32. The second wet press 32 and the associated felts 30 and 31 may be omitted if desired, and the board passed directly from the wet press 28 to the shaping means B. However, sufficient processing should be given the traveling board web so as to insure the drying of the web to such an extent that it will carry its own weight when passed to the shaping means B, and this is ordinarily insured by the provision of the two presses, as shown.

60 65 The shaping means B is shown as compris-

ing a plurality of sets of cooperating rolls having non-plane forming surfaces. Each set of shaping rolls comprises an upper roll 40 and a lower roll 41, which are preferably made adjustable relative to each other in the manner of press rolls. The rolls 40 and 41 are provided respectively with convex and concave cooperating forming surfaces. The relative positioning of the concave and convex surfaces is immaterial, so long as one of the rolls is provided with a convex shaping surface, and the other roll with a complementary concave shaping surface.

The construction of one form of shaping rolls is particularly illustrated in Figs. 4 and 5, the curves of the surfaces of these shaping rolls being shown of an exaggerated size in these figures for purposes of clearer illustration. The lower roll 41 is provided along its length with a plurality of convex curved surfaces 42. Each of these curved surfaces 42 has an overall length which is equal to the length of the barrel stave being manufactured. As an illustration, considering a four-foot barrel stave to be the article being manufactured, each of the surfaces 42 would have a length of four feet the overall length of the roll 40 thus being divided into curved surfaces of the length of four feet. Considering a traveling board web 150 inches wide as being produced on the forming machine A, this web would conveniently form three barrel stave lengths of four feet each across the width of the web, leaving some three inches overlapping at the edge at each side of the web, thus allowing some excess for cutting or trimming. If barrel staves of a length of two feet six inches are being made, such a web conveniently forms five barrel stave lengths across the width. The curve of each of the surfaces 42 is made to conform to the curvature of the bulging type barrel stave being manufactured, so that a bulging container may be formed from these staves. In usual barrel staves of a length of about two feet six inches, the rise of the bulge may be about two to two and one-half inches or more. These figures are not in any way intended to be of a limiting nature, but are merely given as examples to aid in an understanding of the invention.

The upper roll 40 is formed with a plurality of concave surfaces 44 across the length thereof, as shown in Fig. 4. The shape or curvature of the surfaces 44 of the roll 40 is such as to be complementary with the surfaces 42 of the roll 41. The rolls 40 and 41 are adjusted relative to each other to provide preferably a slight clearance between their cooperating forming surfaces. The clearance is such however that the traveling board web passing between these rolls is pressed or squeezed between the forming surface with the result that the web is molded or shaped by these surfaces to the shape of barrel staves.

The shaping rolls are rotated so as to have an effective surface speed which is the same as that of the traveling board web, the two co-operating rolls being preferably geared together with one of the rolls driven from a suitable source of power (not shown). In machines of this character it is found desirable to run the same at relatively low speeds, such as 100 to 200 feet a minute or less.

10 The board web entering the first set of shaping rolls as indicated at 47 is transformed from a flat traveling strip to a traveling strip having a series of connected non-plane or curved upper and lower surfaces, 15 and forming in fact a plurality of connected barrel staves. The upper and lower surfaces of the traveling web as indicated at 48 and 49 respectively correspond to the surfaces of the rolls 40 and 41 respectively when laid out in 20 a plane. In this manner the traveling board web is shaped to form a plurality of barrel staves which are connected to each other at their adjacent edges.

25 Preferably another set of cooperating shaping rolls as indicated at 50 are provided to again exert pressure and a further shaping action upon the board web which has been shaped by the first set of rolls 40 and 41. The second set is provided to perfect the 30 shape of the individual staves of the traveling web, and to counteract any tendency for the staves to pull or spring somewhat out of shape due to the tension in the web.

The formed and shaped web then travels 35 through the drier C. In order to effectively preserve the shape of the web after passing through the shaping rolls, conveying surfaces are preferably provided for the drier which correspond to the shape of the formed 40 web. As shown these conveying surfaces comprise a plurality of rotating rolls 55 positioned beneath the traveling web and in contact with the lower surface thereof. These rolls are shaped to correspond to the shape 45 of the lower rolls of the shaping rolls, and thus have a shape which corresponds to the shape and curvature of the traveling web. The rolls 55 may be steam-heated in the manner of conventional drying cylinders to assist 50 in the drying operation, and are positively driven in any conventional manner at an effective surface speed corresponding to the speed of the web. Preferably the drier is of the tunnel or kiln type having an enclosing casing 56, with an inlet 57 at one end 55 through which heated air is supplied to the interior of the drier and an outlet 58 for the escape of the moistened air at the opposite end.

60 In order to insure the proper formation of the barrel staves, a second group of shaping rolls indicated at 60 is preferably provided after the first drier 56. And conveying rolls shaped to correspond to the shape of the traveling web are preferably provided to convey

the web from the shaping rolls 50 into the drier 56, as indicated at 62, and also to convey the web from the drier 56 to the second set of shaping rolls 60, as indicated at 63. The web received from the first sets of shaping rolls is partially dried in the first drier 56, and then subjected to a second shaping action at the shaping rolls 60. After the second shaping action, the web is then completely dried in the second drier, indicated at 65, 70 which may be similar in construction to the first drier. In a machine of this character, running at a speed of 100 to 200 feet a minute, it is found that a total drying length of about 1000 feet gives a substantially dry web. Satisfactory results are obtained by constructing each of the driers of a length of about 500 feet, and providing an intermediate set of shaping rolls, as shown.

75 The material passing from the final drier is then preferably cut into widths and removed for further processing. For this purpose a cutter or slitter indicated generally at 70 is provided, which cutter may be of conventional character and of the type generally used to cut a traveling web of paper into 80 sheets.

85 In actual practice, the widths of staves thus produced may be cut by a plurality of saws (not shown) into individual staves and then 90 conveyed to cooping machines of conventional character where these individual staves are further processed to form the finished staves.

95 As cooping machines are well-known, and any conventional type of machine may be used for this purpose, no attempt is made to illustrate the same herein. Figs. 6 and 7 illustrate a formed barrel stave before cooping, as it is produced from pulped fibrous material in accordance with this invention. The stave is seen to have a curvature along its length as indicated at 75 which produces the bulge of the finished barrel. The staves as thus produced on the forming machine are then completed on the cooping machines to form the finished staves, as illustrated in Figs. 8 and 9. The ends of the staves are tapered as indicated at 79, and the staves are cut slightly smaller on the inner edge than on the outer, forming a beveled edge as indicated at 80. The staves may also be beveled at the top and bottom edges as indicated at 81 and 82 respectively, to provide beveled edges to receive the cover and bottom of the barrel. The cover and bottom of the barrel or keg may be formed directly from building board formed on a conventional board machine, by cutting the board into circular pieces and beveling these pieces to cooperate with the beveled surfaces of the stave ends.

100 Fig. 10 illustrates a completed barrel formed of pulped fibrous material, and constructed by assembling the individual 105

coopered staves, as indicated at 85 and the cover 86 and bottom 87.

In the embodiment of the invention disclosed and thus far described, the staves as formed are curved or bulged along the length, but are flat across the width. When these staves are assembled to form the completed barrel, and the hoops indicated at 88 are driven on, the staves are bent by the pressure of the hoops so that the assembled staves form a container of circular cross-section. The hoops or binding wire thus hold the individual staves in proper assembled relation in the usual manner.

If desired, the staves may also be given curvature across the width during formation. In Figs. 11 and 12 is illustrated a pair of shaping rolls adapted to impart to the staves during formation both a bulge along the length and a curvature across the width. As illustrated, the lower roll 41' is provided with a plurality of curved surfaces 42' across the length thereof similar to the rolls illustrated in Figs. 4 and 5. Each of the surfaces 42' is also curved across the width, as indicated in Fig. 12 at 90, forming in effect a corrugated roll. This curvature across the width may be such as to provide a barrel stave having a curved surface of a diameter corresponding to the diameter of the barrel which is adapted to be formed therefrom. The curve 90 may vary along the length of the surfaces 42', being of the largest diameter adjacent the center of the surfaces 42' and of the smallest diameter adjacent the ends. This compensates for the difference in the diameter of the barrel at the bulging portion and at the ends, and provides a curved stave which cooperates with a plurality of similar staves to form the completed bulging barrel.

The upper roll 40' is formed with a plurality of concave surfaces 44' across the length thereof, which surfaces are also concaved across the width as indicated at 91' in Fig. 12. The shape or curvature of the surfaces 44' of the roll 40' both along the length and across the width thereof is such as to be complementary with the surfaces 42' of the roll 41'.

Figs. 13 and 14 illustrate a barrel stave of pulped fibrous material as formed on the shaping rolls of Figs. 11 and 12. Each stave thus formed is seen to have a curvature along its length as indicated at 91, which produces the bulge of the finished barrel, and also is curved along its width as indicated at 92 to correspond with the desired diameter of the finished barrel. The staves as thus formed, assume when assembled the proper curvature of the barrel, and do not have to be drawn into shape by the driving on of the hoops or binding wire, the latter serving in this case merely to hold the staves in properly assembled relation.

While the products and method herein described, and the form of apparatus for carry-

ing this method into effect, constitute preferred embodiments of the invention, it is to be understood that the invention is not limited to these precise products, method and form of apparatus, and that changes may be made therein without departing from the scope of the invention which is defined in the appended claims.

What is claimed is:

1. The method of forming non-plane surfaced boards, slats or the like from pulped fibrous material, which comprises forming said pulped fibrous material into a traveling board web, shaping said traveling board web during formation and when still plastic into a plurality of non-plane parts, drying said traveling formed and shaped parts, and then cutting said dried and shaped traveling web into individual parts. 75

2. The method of forming barrel staves from pulped fibrous material, which comprises forming said pulped fibrous material into a traveling board web, shaping said traveling web during formation and when still plastic in simulation of the shape of barrel staves, continuously removing said formed and shaped board web from the shaping zone, and drying said formed and shaped board while maintaining the shape. 80 90

3. The method of forming barrel staves or the like from pulped fibrous material, which comprises forming said pulped fibrous material into wet board capable of sustaining its own weight, shaping said wet board to the desired shape for forming barrel staves, partially drying said formed and shaped board, again shaping said board when partially dried, and finally drying said board. 95 100

4. The method of forming barrel staves or the like from pulped fibrous material, which comprises forming said pulped fibrous material into a traveling board web, shaping said traveling board web during formation and when still plastic to the desired shape for forming barrel staves, drying said formed and shaped traveling web, and cutting said dried and shaped web into barrel staves. 105 110

5. In the manufacture of barrel staves or the like from pulped fibrous material, in which said pulped fibrous material is formed into board and the board is shaped when plastic to the desired shape to form barrel staves, the method of drying said formed and shaped board which comprises drying the same to a substantially rigid state, and guiding it during the drying process in a substantially continuous direction on a surface shaped to correspond to the shape of said board. 115 120

6. In the manufacture of barrel staves or the like from pulped fibrous material, the method which consists in forming said pulped fibrous material into board, and shaping said board during formation and while still plastic by molding to a gradual curvature to form bulging-type barrel staves. 125 130

7. Apparatus of the character described, comprising in combination, board-forming means, shaping rolls having cooperating non-plane surfaces simulating the shape of barrel 5 staves, and drying means provided with surfaces shaped to correspond to the shape of said shaping rolls.

8. Apparatus of the character described, comprising in combination, board-forming means, shaping rolls having cooperating non-plane surfaces simulating the shape of barrel staves, means to partially dry the formed and shaped board, additional shaping rolls shaped to correspond to the shape of said first shaping 10 rolls, and means to finally dry said formed and shaped board.

9. Apparatus of the character described, comprising in combination, means for forming a traveling board web, and shaping rolls 20 having complementary non-plane surfaces simulating the shape of barrel staves adapted to receive said traveling web from the forming means and to mold said web to the desired shape of barrel staves as the web travels 25 through said shaping rolls.

10. In apparatus of the character described adapted to form curved boards or laths for use as barrel staves or the like from a traveling web of pulped fibrous material, shaping 30 means comprising cooperating shaping rolls provided with convex and concave forming surfaces respectively shaped to simulate the shape of barrel staves.

11. For use in apparatus of the character 35 described adapted to form barrel staves from a traveling board web of pulped fibrous material, cooperating shaping rolls having a plurality of complementary convex and concave forming surfaces respectively along the 40 length thereof, each of said curved forming surfaces simulating the shape of a barrel stave.

12. For use in apparatus of the character 45 described adapted to form non-plane surfaced boards or laths from a traveling web of pulped fibrous material, in which the traveling web is shaped while plastic to the desired non-plane shape, drying means for said formed and shaped traveling web comprising 50 a drying chamber through which said web travels in a substantially continuous direction, and a guiding surface therein for said traveling web, said surface being shaped to correspond to the shape of said web.

55 13. Apparatus of the character described comprising in combination, board-forming means, said board-forming means being adapted to form a continuously traveling board web, shaping means having complementary non-plane surfaces adapted to receive the board web from said board-forming means and to continuously mold it to a corresponding shape, and drying means including a drying chamber through which the 60 shaped web passes in a substantially straight 65

course, said drying chamber having a supporting surface for the web shaped to correspond to the shape of said molded board web.

In testimony whereof I hereto affix my signature.

ALEXANDER R. WALTON.
